SPRAY APPARATUS WITH OSCILLATORY
DISCHARGE MEANS

Joe N. Welch, Walpole, Mass.

Application November 15, 1946, Serial No. 710,140

3 Claims. (Cl. 299—62)

1

My present invention relates to fluid spraying, sprinkling and diffusion, and to shower and sprayer systems and apparatus for discharge of liquid or gaseous fluid. While of general utility the apparatus and devices of the invention are particularly useful in paper making and in textile and other fibre liberating, treating and handling, and in general for washing, cleaning, flushing and like treatment of drums, screws, molds, cylinders, rolls and of various chambers, containers and the like, especially where space limitations are an important consideration.

More particularly the invention aims to provide so-called shower-pipes, sprinkler-tubes and the like bodily fixed or movable means of the class described of simplified and otherwise improved construction and arrangement, easy to install and economical to operate, including novel discharge elements and actuating mechanism whereby the discharging fluid may be subject to oscillation of the discharge members during operation of the apparatus and system.

In the drawings illustrating by way of example one embodiment of the invention:

Fig. 1 is a longitudinal sectional view, partly diagrammatic, of a shower-pipe unit of the system;

Fig. 2 is a longitudinal section of a nozzle for the unit of Fig. 1, on a larger scale; and

Fig. 3 is a plan of the nozzle of Fig. 2, looking at the discharge end.

Referring to the drawings in more detail, the system of the invention includes one or more units such as that of Fig. 1. The assembly as there shown comprises a hollow cylindrical shell, tube or pipe 5 of any length appropriate for the particular installation, as indicated by the intermediate broken-away portion in Fig. 1. The pipe 5, which may be of bronze or other preferably corrosion-resistant material, is supported in operative position as by an end coupling or bearing collar 7 having threaded or other connection with one end of the pipe as at 6.

The pipe-supporting coupling collar 7 adapts the shower unit for mounting on the appropriate supporting part 8, that shown somewhat diagrammatically in Fig. 1 being representative of any part available for the purpose at the particular installation. The selected part 8 is generally but not necessarily stationary. It may for example be a portion of or a bracket or like part attached to the frame of a paper-making or fibre-handling machine, a head or spider of a drum, a wall of a chamber from which an accumulation of fibres or other matter is to be re-

leased, and corresponding parts for apparatus of the particular industry concerned. For illustration the pipe 5 is shown in a general horizontal position but the entire unit is adapted for operation in any preferred arrangement with respect to the horizontal.

In the present example the mounting collar 7 is formed with a flange 9 bolted in fluid-tight relation to the supporting part 8. Thus the shower pipe 5 and associated parts as illustrated may be supported at but one end, as at the left in Fig. 1, adapting the unit for introduction into more or less closed or restricted spaces. Where the circumstances of use permit the unit may be otherwise supported. The fluid to be sprayed or diffused may be admitted directly to the pipe 5 at any convenient point along it or via the mounting collar 7. As shown in Fig. 1 the latter has a fluid inlet 10 for threaded or other connection to a fluid supply conduit 11. The end 12 of the shower pipe 5 distal from the supporting end 6 is closed and sealed as by a threaded cap 13.

An important feature of the invention is the construction and arrangement of the shower unit so that the elongated tubular element or pipe 5 itself constitutes the main housing, guide and support for the unit, also is the conduit for the fluid supply from the inlet 10 and in addition forms the tubular spray head proper from which the shower jet or spray discharge takes place, herein at the one or more nozzles thereon, to be described. This contrasts with known apparatus requiring two or more tubes or pipes in general parallelism and either laterally spaced or concentric. In the improved assembly unit of the invention the single pipe or tube 5 serves the plural functions of housing, support, guide, supply conduit and discharge head.

Accordingly the cylindrical wall of the pipe 5 is apertured to accommodate one or more and generally a multiplicity of fluid discharge means in the form of spray, jet or shower nozzles designated generally at 15, 15 in Fig. 1, one of them being shown separately in Figs. 2 and 3. These nozzles 15 are distributed along the pipe 5 in any desired spacing and arrangement usually including one or more longitudinal rows.

Referring more particularly to Figs. 2 and 3, each nozzle 15 comprises a cup-like tubular body or nozzle proper 16 including at the inner end a threaded nipple 17 for reception in a corresponding aperture on the wall of the pipe 5. The outer end of the nozzle body 16 has a central outlet opening 18 preferably conically flared as shown to provide for the desired angular range of the

spray or jet, generally 10° to 20° or more about the central axis of the nozzle. Centrally within the body 16 is a chamber 19 circular in cross-section or substantially so, as seen dotted in Fig. 3. This chamber provides a bearing guide for the movable and generally spherical or ball-form discharge member 30 to be described.

The wall of the chamber 19 is annularly recessed to receive a removable snap ring 20, Fig. 2, spaced from the outlet 18 sufficiently to accommodate the discharge member 30. This ring forms a retaining abutment for the discharge member 30 and provides a seat therefor at certain times, as when the fluid flow is shut off. The outer end of the chamber 19 is provided with low-friction bearing and packing means 22 for the discharge member 30. Such means as shown may be in the form of a grommet or bearing washer having a central aperture conformant to the outlet 18 of the nozzle and dimensioned to seat snugly within the adjacent end of the chamber 19. The aperture-surrounding wall of this bearing and packing member 22 is inwardly flared substantially as indicated in Fig. 2 to provide a conical bearing and sealing seat for the discharge member 30. Said member 22 may be of rubber or a rubberous material suitable for sealing purposes and adapted for low-friction bearing engagement with the discharge member 30 having regard to the material of the latter and as appropriate for the fluid to be distributed which may be water or other liquid or a gas including air.

Thus the nozzle body 16, ring 20 and washer 22 provide an outwardly sealed cage and universal guide-bearing for the discharge member 30 now to be described. In accordance with the invention this discharge member proper is constructed and arranged for oscillation in a plane generally longitudinal of the pipe 5. It also is universally adjustable bodily with respect to the axis of the nozzle 16 so that the plane of oscillation may be angularly varied about the pipe axis. Accordingly this discharge member 30 is of ball form or substantially spherical. It is proportioned to have a movable bearing fit in the chamber 19 where it is operatively located and guided by the chamber wall and the concave or conically tapered washer 22, and at times by the ring abutment 20.

The ball-form discharger, jet or spray-forming member 30 has at the outer segment a discharge orifice 32 of selected size and shape and which communicates inwardly with a diametral passage 33 in the ball. A fluid admitting channel 34 extends between the passage 33 and the lower segment of the ball member 30 where it is open to fluid as at 35. A radial stem 37 is threaded or otherwise fixed at the lower central portion of the ball member as in a tapped recess 38. To facilitate manufacture the diametral passage 33 is formed as a non-threaded continuation of the stem-attaching recess 38. Conformantly the fluid channel 34 may be angularly offset substantially as shown. The stem 37 projects at the open end of the nozzle-supporting nipple 17 and has integrally or otherwise secured at the projecting end an operating finger or lever 40.

The assembly unit of the invention further comprises means for oscillating the discharge member or members 30 during operation of the system and apparatus and in accordance with selected timing and extent for the motion imparted. In the illustrated embodiment the means for this purpose is constructed and arranged and so related to the discharge jet or spray means proper

as to impose a minimum load and proportionately to reduce power consumption.

Referring to Fig. 1, the operating fingers or levers 40 of the entire plurality of nozzles 15 are operatively associated with a connector herein comprising a tie bar or rod 45 extending longitudinally within the conjoint tubular housing, conduit and spray head or shower pipe 5. Opposite each nozzle 15 the rod 45 has provision for demountable connection with the corresponding operating finger 40. Each such connection as shown comprises a diametral recess 46 through the rod 45 and tapered inward from one or both sides thereof. The recess portion of minimum diameter forms an annular fulcrum 47 for pivotal and sliding association with the corresponding finger 40. Said fingers or levers 40 are proportioned to fit removably in the fulcral seats 47 with a minimum of lost motion.

In assembling the shower unit, and assuming that the rod 45 is in the neutral or longitudinally central position as shown, the fingers 40 of the several nozzles 15 are inserted at the nozzle-mounting aperture of the tube or pipe 5 and inwardly through the corresponding radially opposite connection recess 46 of the tie rod 45. Since the fingers 40 are rotatively free in the connecting recesses 46, the nozzles 15 may readily be turned down into the installed position of Fig. 1, from which they are readily demountable each as a unit, for cleaning and replacement or substitution.

The nozzle-operating connector or tie rod 45 is movably carried herein by a pair of opposed bellows 50 and 51 of similar size and capacity, one at each end of the rod and in mutual alignment in the tube or pipe 5. The opposed inner end walls 52, 53 of the bellows have internal axial bosses 54, 55 centrally tapped at the outer ends for threaded connection with the corresponding ends of the tie rod as at 56, 57. The outer end walls 58, 59 of the two bellows are formed at their outer faces with central supporting studs or bosses 60, 61. The boss 61 for the bellows 51 at the right in Fig. 1 is threaded and sealed in a corresponding tapped aperture in the end closure cap 13. An air-duct 63 extends through the boss 61 and the end wall 59 of the bellows, providing communication between the interior thereof and atmosphere. At the other or supporting end 6-7 of the pipe assembly the mounting boss 60 for the bellows 50 is tubular and is extended in sealing relation through and projects beyond the particular pipe-supporting part 8. This tubular boss 60 is externally threaded to receive an anchor nut 64 at the opposite face of the part 8 which latter also may have threaded engagement with the boss.

The bellows 50 at the supporting and operating end 6-7 of the shower unit further has associated with it an actuating rod 70, the inner end of which is secured as by threading at 71 to the inner end of the boss 54 on the inner end wall 52 of the bellows 50. This actuating rod or actuator 70 extends freely out through the outer end wall 58 of the bellows 50 and axially through the tubular boss 60 with capacity for axial sliding movement in and relative to said parts as bearings. Communication between the interior of the bellows 50 and atmosphere is provided in any convenient manner as by an air duct 74 in the actuator 70.

The outer end of the actuator 70 is operatively associated with any preferred power source, motor, oscillator or reciprocating part such as indi-

cated diagrammatically at M in Fig. 1. Such operating medium if hydraulic may derive energy from or be operatively subject to the pressure of the fluid to be sprayed.

It will be understood that the entire interior of the housing and conduit tube or pipe 5 and of the tubular support 70 is uniformly subject to the pressure of the water, air or other fluid to be sprayed, coming from the supply line 11 and entering at the inlet 10. The aligned bellows pair 50, 51 operates in balanced opposition. Thus in the central or neutral position of the parts as in full line in Fig. 1, the fluid pressure at the inner face of one of the bellows balances that in the opposite direction at the other bellows. Hence there is substantially a zero load effective in either direction with respect to the actuating rod 70. The latter accordingly is readily subject to reciprocating movement with minimum effort from the oscillator, motor or operating means M. During operation of the shower apparatus oscillation imparted by the medium M to the actuator rod 70 alternately shifts the latter and the connector rod 45, the nozzle fingers 40 and the discharge members 30 in one and the opposite directions. The extent of axial reciprocating travel by the connector 45 and hence the angular movement of the several discharge members 30 and also the timing thereof, whether at regular intervals or otherwise, may be regulated and controlled at the operating medium M. Travel toward the right in Fig. 1 as indicated by the right-hand dotted positions of the nozzle levers 40 compresses the bellows 51 and correspondingly extends the opposite bellows 50, maintaining a balance of forces upon the movable parts, exclusive of that imparted by the actuator 70. A like but reverse balancing action attends the travel toward the left. The result is a sweeping movement of the jet or spray discharge from the one or more nozzles 15 alternately in opposite directions lengthwise of the tubular unit.

My invention is not limited to the particular embodiment thereof illustrated and described herein, and I set forth its scope in my following claims.

I claim:

1. A shower assembly unit comprising a cylindrical tube closed at the ends and adapted for support at one of them, a fluid inlet to the tube, the cylindrical wall of the tube having a plurality of longitudinally spaced mounting apertures, a like number of spray nozzles installed at the respective apertures, each nozzle comprising a tubular chambered body with centrally open inner and outer ends, a ball discharge member movably held and guided in the body chamber and an operating finger projecting from the ball member and through the inner end of the nozzle body, a connector for the several fingers longitudinally disposed in the tube, opposed bellows subject to fluid pressure in the tube and supporting the connector for pressure-balanced oscillation

thereof lengthwise of the tube, and oscillatory actuator means operatively associated with the connector.

2. A shower system for fibre-handling, paper-making and other machines, comprising an elongated tubular body closed at the ends and having an inlet for fluid, the closure at one end including means for mounting the body on a supporting part, a multiplicity of nozzles distributed along and in fluid communication with the body and directed generally radially thereof, a discharge directing member carried in each nozzle with capacity for oscillatory movement in a plane longitudinal and substantially diametrical of the body, a radially inwardly extending operating finger on each discharge directing member, a connector rod housed and guided for lengthwise movement in the body and operatively connecting the operating fingers of the several discharge directing members, a power-operated oscillator, and means whereby the oscillator actuates the connector rod to move the discharge directing members in unison in one and the opposite direction in said plane.

3. In a shower-pipe unit, an elongated tubular supporting and housing supply and discharge conduit having closing end walls and adapted for mounting at one of them a plurality of nozzles individually spaced along the conduit and communicating with the interior thereof, an oscillating discharge member in each nozzle, an operating rod housed in the conduit and commonly connected with the nozzle discharge members, a pair of opposed balancing bellows mounted in the conduit at the respective end walls, the operating rod being connected at the opposite ends to the respective bellows axially thereof, an inlet for fluid to the conduit, and actuator means to move the rod alternately in opposite longitudinal directions thereby to oscillate the discharge from the nozzles.
